BOBBIN CLUTCH

George H. Magrath, Whitinsville, Mass.

Application March 9, 1939, Serial No. 260,680

5 Claims. (Cl. 242—46.6)

This invention relates to bobbin clutches of the type having expandible clutching members which maintain the bobbin firmly in position during the spinning operation.

In bobbin clutches of the aforesaid type the lower ends of the clutching members are usually either mounted directly on the whirl or are supported so that they extend into a recess formed in the upper face of the whirl, and in either case their contacting surfaces usually extend through openings formed in a case which is secured to the blade independently of the whirl. Such constructions are subject to the objection that due to repeated doffing of the bobbin the whirl is apt to be driven down on the blade, thus separating it from the case with a consequent displacement of the clutching members which renders them inoperative. A further objection to such constructions is that when the clutching members are contracted by the bobbin there is produced about their free ends a gap in which lint collects, with the result that the operation of one or more of the clutching members is impaired. Consequently, the bobbin is not maintained properly centered and considerable damage may result, particularly when operating at high speeds.

The principal objects of the present invention are to provide a bobbin clutch which overcomes the aforementioned difficulties and to provide a bobbin clutch which is of simple design and of strong and durable construction, which is efficient and reliable in operation, and which can be manufactured at a relatively low cost.

Further objects relate to various features of construction, and will be apparent from a consideration of the following description and accompanying drawing, wherein:

Fig. 1 is an elevation, with parts broken away and shown in section, of a bobbin clutch constructed in accordance with the present invention;

Figs. 2 and 3 are sections on the lines 2—2 and 3—3, respectively, of Fig. 1;

Fig. 4 is a longitudinal section illustrating a modified embodiment of the invention;

Fig. 5 is a top plan view of the clutch spring of the embodiment shown in Fig. 4 prior to performing the shaping operations; and

Fig. 6 is a section on the line 6—6 of Fig. 4.

The embodiment shown in Figs. 1 to 3 comprises a blade 1 having a whirl 2 mounted thereon, the upper face of the whirl being formed with a recess 4 to accommodate the lower end of a

bobbin clutch comprising a generally cylindrical member 5 having a dome-like cap or head 6 which has a press fit on the blade 1, and a plurality of depending fingers 7 and 8 integral with the head 6. A retaining member 10 loosely fits within the recess 4 of the whirl and is formed with an annular recess 11 which receives the lower ends of the fingers 7 and 8.

As here shown by way of illustration, the clutch 10 may be made from a generally cylindrical case by cutting its skirt portion longitudinally to provide spring fingers 7 and stationary fingers 8 of substantially greater width than the spring fingers 7. After having formed the fingers 7 and 15 8, the case may then be swaged in suitable dies so as to compress the fingers 7 and form convex surfaces which bulge outwardly beyond the adjacent fingers 8, and after having performed the shaping operation the case may then be tempered 20 so as to impart the desired degree of resiliency to the fingers 7.

The lower ends of the fingers 8 have a press fit within the recess 11 and thus support the member 10 independently of the whirl. The fingers 7, after having been treated as above described, are substantially thinner than the fingers 8 and their lower ends loosely fit the recess 11, the walls of which constitute stops limiting their inward and outward flexing movements. The construction and arrangement of the parts are such that the spring fingers 7 are normally held against the outer wall of the recess 11 and are thus positioned frictionally to hold a bobbin in place. Since the spring fingers 7 adjoin the stationary fingers 8 and are normally held against the outer wall of the recess 11, all gaps and recesses are substantially eliminated, thus minimizing, if not overcoming, the danger of lint collecting about these parts.

40 When a bobbin B is applied about the blade, its base seats on the upper face of the whirl and the wall of its bore engages the spring fingers 7 which are flexed inwardly about their upper ends, their inward movement being limited by the engagement of their lower ends with the inner wall of the recess 11. Although repeated doffing of the bobbin may result in driving the whirl downwardly on the blade, it will be noted that 45 such displacement of the whirl does not affect or in any way impair the operation of the clutch mechanism.

In the embodiment shown in Figs. 4 to 6, the clutch mechanism 5a comprises a clutch spring 55 having a substantially flat body portion 15 formed

with a central opening to accommodate the blade 1, and a plurality of depending expandible spring fingers 16. The clutch spring may be made from a substantially flat spider-shaped metal blank B1 (Fig. 5) which is subjected to swaging operations in suitable dies to form fingers 16 having convex surfaces between their ends.

The clutch spring is held in position by the upper end of an inner case or supporting member 18 which has a press fit on the blade 1 and is positioned to clamp the body portion 15 against a cap piece 20 which also has a press fit on the blade 1. The cap piece 20 is preferably dome-shaped with its base portion conforming to the upper end of the clutch spring so as to present a smooth, substantially continuous surface therewith. The lower end of the supporting member 18 is provided with a flange 22 formed with a recess 24 in which the free ends of the spring fingers 16 having a loose fit, the walls of the recess 24 constituting stops which limit their flexing movement as in the previously described embodiment.

In each of the embodiments herein shown, the clutch spring is firmly clamped in fixed position relative to the blade, and hence is securely anchored so as to withstand the shocks and stresses encountered in spinning operations. It will be further noted that in each of the embodiments the clutch mechanism and associated parts are supported independently of the whirl, and even though the whirl may be displaced by repeated doffings, the clutch mechanism nevertheless remains operative. Moreover, the construction and arrangement of parts are such as to minimize, if not eliminate, an accumulation of lint or other extraneous matter about the clutch members, and hence a more reliable operation and a lower maintenance cost is assured.

While I have shown and described certain desirable embodiments of the invention, it is to be understood that the present disclosure is for the purpose of illustration and that various changes in shape, proportion, and arrangement of parts, as well as the substitution of equivalent elements for those herein shown and described, may be made without departing from the spirit and scope of the invention as set forth in the appended claims.

I claim:

1. A bobbin clutch comprising a blade, a whirl mounted on said blade for supporting the lower end of a bobbin, said whirl having a circular recess concentric with said blade, and clutching means mounted on said blade above said whirl for holding the bobbin in position on said whirl, said clutching means including a head member fixed to said blade and a plurality of depending fingers circumferentially disposed about said blade and including outwardly bowed flexible spring fingers for frictionally holding the bobbin, said depending fingers defining an outer surface free from yarn-collecting irregularities and substantially preventing the entrance of yarn into the interior of the clutch, and an annular retaining member positioned within said recess in spaced relation to said blade, said retaining member having an annular recess in which the lower ends of said depending fingers are received, said head member, depending fingers and retaining member constituting a unit structurally independent of said whirl and said retaining member being of such size and shape that it does not contact a bobbin when applied to, removed from, or seated on said whirl.

2. A bobbin clutch comprising a blade, a whirl mounted on said blade for supporting the lower end of a bobbin, and clutching means mounted on said blade above said whirl for holding the bobbin in position on said whirl, said clutching means including a head member fixed to said blade and a plurality of integral depending fingers circumferentially disposed about said blade and including alternate outwardly bowed flexible spring fingers adapted frictionally to hold the bobbin in position, said fingers defining an outer surface free from yarn-collecting irregularities and substantially preventing the entrance of yarn into the interior of the clutch, and a retaining member circumscribed in spaced relation about said blade and providing means for limiting the action of said alternate fingers, said head member, depending fingers and retaining member constituting a unit structurally independent of said whirl and said retaining member being of such size and shape and being so positioned that it does not contact a bobbin when applied to, removed from, or seated on said whirl.

3. A bobbin clutch comprising a blade, a whirl mounted on said blade for supporting the lower end of a bobbin, and clutching means mounted on said blade above said whirl for holding the bobbin in position on said whirl, said clutching means including a head member fixed to said blade and a plurality of integral depending fingers circumferentially disposed about said blade and including alternate outwardly bowed flexible spring fingers adapted frictionally to hold the bobbin in position, said fingers defining an outer surface free from yarn-collecting irregularities and substantially preventing the entrance of yarn into the interior of the clutch, and a retaining member formed with an annular recess concentric with said blade, the lower ends of said alternate fingers loosely fitting within said recess and the lower ends of said other fingers having a pressed fit within said recess and supporting said retaining member independently of said whirl, said head member, depending fingers and retaining member constituting a unit structurally independent of said whirl and said retaining member being of such size and shape and being so positioned that it does not contact a bobbin when applied to, removed from, or seated on said whirl.

4. A bobbin clutch comprising a blade, a whirl mounted on the blade for supporting the lower end of a bobbin, and clutching means mounted on said blade above said whirl for holding the bobbin in position on said whirl, said clutching means including a cap fixed on said blade in spaced relation to said whirl, a clutch spring having a body portion fitting against said cap and a plurality of circumferentially disposed depending spring fingers, and means supported independently of said whirl and defining an annular recess in which the lower ends of said spring fingers are received for limiting their inward and outward flexing movements, said cap, clutching means and the means limiting the flexing movements of said spring fingers constituting a unit structurally independent of said whirl.

5. A bobbin clutch comprising a blade, a whirl mounted on the blade for supporting the lower end of a bobbin, and clutching means mounted on said blade above said whirl for holding the bobbin in position on said whirl, said clutching means including a cap fixed on said blade in spaced relation to said whirl, a clutch spring having a body portion fitting against said cap

and a plurality of circumferentially disposed outwardly bowed depending spring fingers defining an outer surface free from yarn-collecting irregularities and substantially preventing the entrance of yarn into the interior of the clutch, and a supporting member having its upper end fixed to said blade and clamping the body portion of said clutch spring against said cap, the

lower end of said supporting member having a flange formed with an annular recess in which the lower ends of said spring fingers are loosely received so as to limit their flexing movements, 5 said cap, clutch support, and supporting member constituting a unit structurally independent of said whirl.

GEORGE H. MAGRATH.
